CHARCOAL BRIQUETTE SIEVE

Calvin Gould, Peabody, Mass.
(11 Riverside Ave., Apt. 12, Danvers, Mass. 01923)

Filed Oct. 9, 1973, Ser. No. 404,137

Term of patent 14 years

Int. Cl. D7—08

U.S. Cl. D7—206

FIG. 1 is a perspective view of a charcoal briquette sieve embodying my new design;

FIG. 2 is a front elevational view thereof;

FIG. 3 is a top plan view thereof; and

FIG. 4 is a side elevational view thereof.

I claim:

The ornamental design for a charcoal briquette sieve substantially as shown and described.
